(57) **CLAIM**

The ornamental design for a container with brush and cap, as shown and described.

DESCRIPTION

FIG. 1 is a perspective view of a container with brush and cap showing our new design;

FIG. 2 is a side elevational view thereof;

FIG. 3 is an elevational view of the side opposite that shown in FIG. 2;

FIG. 4 is a front elevational view thereof;

FIG. 5 is a rear elevational view thereof;

FIG. 6 is a top plan view thereof; and,

FIG. 7 is a bottom plan view thereof.

The broken line boundary and the area within that boundary shown in FIG. 7 illustrate a portion of the container that forms no part of the claimed design.
